SOUND AMPLIFIER MUTING MEANS

Eugene F. McDonald, Jr., Chicago, Ill.

Application September 26, 1945, Serial No. 618,758

4 Claims. (Cl. 250—20)

1

The present invention relates to radio receivers, sound amplifiers and the like and, in particular, to a system and means for silencing apparatus of that type for a predetermined time interval.

In listening to the reproduction of sound from a radio receiver, a sound amplifying device, phonograph, recorder, etc., it may be desirable to control or interrupt the sound transmission for a predetermined time interval as, for example, when riding in an automobile and listening for train whistles or bells at a railroad crossing, when conversing with other persons or when undesirable sounds are emitted from such apparatus. In such cases it is desirable to effect such a control with ease.

It is therefore an object of the present invention to provide a novel control for apparatus of the type specified in which the apparatus may be silenced easily and automatically for a predetermined time interval.

The type of control contemplated in the present disclosure is particularly applicable to present day broadcast receivers over which repulsive advertising matter of an annoying nature is transmitted. When applied to such receivers it is desirable that the control be automatic in operation to restore the receiver to fully operative condition after the duration of such advertising matter.

Another object of the present invention is to provide a novel arrangement in which a radio receiver may be squelched for a predetermined time interval, approximately twenty seconds, commensurate with the duration of an average "commercial" of advertising matter.

The present control finds great applicability in automobile radio receivers which are controlled at or near the floor board of an automobile in accordance with the teachings in my prior patents. In such case an operator need not hold the control down for a prolonged period of time as in my prior Patent No. 2,374,873, granted May 1, 1945, but need only touch and release a button in which case the receiver is squelched and is then restored automatically to fully operative condition after a predetermined period of time without requiring the attention of the driver whose attention, of course, for the purpose of safety, is needed elsewhere.

Still a further object of the present invention is to provide a novel muting arrangement in the control shown in my above mentioned prior patent.

The features of the present invention which are believed to be novel are set forth with particularity in the appended claims. The present invention itself, both as to its organization and manner of operation, together with further objects and advantages thereof, may best be understood by reference to the following descrip-

2

tion taken in connection with the accompanying drawings in which:

Figure 1 shows a part of the interior of an automobile in which apparatus incorporating the present invention is mounted;

Fig. 2 shows structural and schematic circuit arrangements incorporating the control apparatus shown in Fig. 1;

Fig. 2A shows a fragmentary sectional view of a portion of the apparatus shown in Fig. 2;

Figs. 3-5, inclusive, show enlarged fragmentary sectional views of apparatus in Fig. 2 in different operating positions;

Figs. 6-8, inclusive, show preferred modified apparatus in different operating positions thereof for practicing the present invention, and

Figs. 9 and 10 show other modified structures for practicing the present invention.

This invention is particularly applicable to maintain a radio receiver silent for a predetermined period of time after actuation of a control which incorporates inherent means to restore the receiver to fully operative condition after a predetermined time interval. In accordance with the present invention, the control may accomplish the desired result by producing a delaying action either by electrical means as shown in Figs. 1-5, inclusive, and Fig. 9, or by mechanical means as shown in Figs. 6-8, inclusive. Also, in accordance with the preferred embodiment of the invention, for safety's sake, the control is maintained on the floor board in an automobile where it is readily accessible for foot operation by the operator of a moving automobile without the necessity for him to remove his hands from the steering wheel, but it will be apparent that the control shown may be mounted elsewhere in an automobile, for example, on the steering post in a position accessible for operation by the knee or leg of the driver. Furthermore, it will be apparent that the apparatus shown herein may be mounted elsewhere than in an automobile, for example in a household receiving system where it will function equally well.

Referring to the electrical arrangement for producing a delaying action shown in Figs. 1-5, inclusive, the control having the general reference numeral 1 is mounted on the floor board 2 of an automobile where it may be actuated easily by the driver without either removing his hands from the steering wheel or taking his eyes off the road.

The control 1 functions not only to produce muting, station changing and volume controlling of a radio receiver having the general reference numeral 3 as shown and described in my prior Patent 2,346,177 granted April 11, 1944, but serves also to produce what I term "delayed muting."

By "delayed muting" in this specification and

claims it is understood that no reference is made

to the ordinary type of clock control but reference is made to silencing or partly silencing, by actuation of a single control, the transmission of sound for a predetermined relatively short time interval after which interval the single control assumes its normal position and condition and sound transmission is automatically restored without manipulation of another or the same control, the restoration of sound transmission being accomplished by utilizing energy which is simultaneously either stored or applied in response to actuation of such single control in effecting the action of silencing or partly silencing.

Referring specifically to Fig. 2, the receiver 3, tuned by the tuner having the general reference numeral 4, is arranged to receive signals on antenna 5 and to reproduce the sound components in speaker 6, the volume of the sound components being controlled by volume control resistance 55 incorporated in the control 1 which has foot control knob 8 arranged to be rotated for volume control purposes and to be moved longitudinally for "delayed muting", muting and station changing.

The receiver is tuned by inductance coils 9, 10, each of which has an inductance value determined respectively by the relative positions of the tuning cores 11, 12, the tuning cores being positioned by the tuning mechanism described presently.

The tuner 4 is of the so-called "turret" tuner type and tuning may be accomplished in a progressive sense by turning manual tuning knob 13 which may be journaled for rotation at some convenient place, for example on the dashboard 14 of the automobile. As will be seen presently, the knob 13 serves not only to produce so-called "continuous" tuning but serves also to adjust the turret tuner for so-called "sequential" tuning.

Such "sequential" tuning of the associated receiving apparatus may be effected by sequential operation of the control 1 controlled by the driver of the automobile. That is, the arrangement illustrated in Fig. 2 tunes the radio apparatus, of which tuning inductances 9 and 10 are a part, either upon actuation of the manual tuning knob 13 or the control 1 which serves to close and open a switch 15 comprising contacts 16, 17.

The inductances of coils 9 and 10 determine the frequency of the received signals and these inductances are varied respectively, by adjusting the position of tuning cores 11 and 12 of relatively high permeability with respect to coils 9 and 10. Only two tuned inductance coils are shown in Fig. 2 for simplicity, but it should be understood that more than two, and preferably three or four of such coils, are tuned simultaneously by positioning relatively high permeability members similar to members 11 and 12 with respect to inductance coils which are connected in the radio receiving apparatus. The tuning members or control members, such as members 11 and 12, are carried on a movable carriage 18, which is secured upon a rod 19 connected to a movable solenoid core 20. The rod 19 has its forward end 21 built so as to cooperate with one of a plurality of stops or abutments 22 of the turret assembly 23; and these stops 22 are adjustably held in the turret assembly 23 by cooperating screw threads on stops 22 and turret assembly 23 as shown in detail in Fig. 2A.

The turret assembly 23 is secured upon a rotatable shaft 24 which carries a ratchet wheel 25 engaged with a pawl 26 so as to rotate the shaft 24 one step or one-sixth of a revolution for each

reciprocation of the pawl 26. The pawl 26 is pivotally mounted on an arm 27 which swings about the shaft 24 and is pivotally and slidably connected to one arm of a bell crank 28 having its other arm pivotally and slidably connected to a lever member 29, the latter being pivoted on a fixed pivot pin 30. The lever member 29 extends from its pivot pin 30 and has a slot 32 to accommodate a pin 33 secured upon the rod 19. The upper end of the lever 29 is preferably positioned so as to be visible and cooperates with the scale 24 having suitable graduations thereon whereby a suitable indication of the position of rod 19 and tuning members 11 and 12 is obtained.

With the apparatus thus far described in Fig. 2, it is clear that when rod 19 moves to the left in the direction of its axis, the bell crank 28 rotates behind an adjacent tooth on the ratchet wheel 25, and that when the rod 19 returns to the right the ratchet wheel 25 is rotated one-sixth of a revolution to a position where an adjacent stop 22 on turret assembly 23 limits further movement of the rod 19 and inductance tuning members 11 and 12 carried thereon. The manner in which the solenoid core 20 and associated rod 19 are actuated upon energization of the associated solenoid 35 is described now.

When solenoid 35 is energized, for example by producing a current flow through the switch 15 comprising contacts 16 and 17 and described in detail later, solenoid core 20 and rod 19 are moved to the left in Fig. 2 to a position where switch contacts 36, 37 of switch 38 are in circuit closing position. Upon deenergization of the solenoid 35 by allowing switch contacts 16, 17 of switch 15 to assume its normally opened position, the solenoid core 20 is returned to its furthest position to the right in Fig. 2 under the influence of tension spring 39 having one of its ends fastened to the lever member 29 and its other end fixed on, for example chassis 40, after pawl 26 has turned the turret assembly 23 an angular distance corresponding to the angular distance between adjacent stops 22.

In summary, when solenoid 35 is energized due to current flowing therethrough and through switch 15 from voltage source 41, solenoid 19 is moved to the left against the action of tension spring 39, and the pin on rod 19 engages lever 29 which pivots about its pivot pin 30 so as to rotate the bell crank 28 counterclockwise around its pivot member. When and as bell crank 28 moves thus counterclockwise, the arm pivotally mounted on shaft 24 and having pivotally mounted thereon pawl 26 rotates counterclockwise about its supporting shaft 24 a distance somewhat greater than one-sixth of a revolution so as to allow pawl 26 to drop behind and engage an adjacent tooth on ratchet wheel 25. When solenoid 35 is deenergized due to the opening of switch 15, tension spring 39 causes clockwise movement of the lever arm 29 and causes the turret assembly 23 to be moved an angular distance corresponding to the angular distance between teeth on ratchet wheel 25, which distance corresponds to the angular distance between stops 22.

Stops 22 are adjustably mounted in turret member 23 and the relative position of each particular stop 22 in turret member 23 determines the distance tuning members 11 and 12 project respectively within inductance coils 9 and 10 after the turret member 23 is rotated around to a position where that particular stop 22 limits movement of rod 19.

It is thus clear that when foot operated switch 15, which is connected in a series circuit with voltage source 41 and solenoid 35, is closed, solenoid 35 draws the core 20 to the left and causes the arm 27 to rotate one step corresponding to the angular distance between stop members.

Therefore, in order to tune the receiver by actuating the foot operated switch 15, it is necessary that the switch 15 be sequentially closed and opened until a particular stop 22, corresponding to a desired station, limits movement of rod 19, whereas, when it is desired to tune the receiver continuously over a range, the manual tuning knob 13, preferably located on the dashboard, is rotated. For the purpose of providing continuous tuning, as well as providing an adjustment for the stops in the turret assembly, the knob 13 is coupled to gear 42 through shaft 43. Gear 42 is arranged to engage at least one of the stop gears 44 which, as shown in Fig. 2A, is threaded in stop assembly 23 and is confined within a hollow portion of turret assembly 23 by the walls 45 and 46. Conventional means, not shown, are provided to prevent rotation of stop 22 when gear 42 is turned. When knob 13 is turned manually, the stop 22 is turned in or out of the turret assembly 23 in a direction depending upon the direction of rotation of knob 13; and rod 19 which is pressed against stop 22 by tension spring 39 follows the movement of the stop member 22. The position of rod 19, as explained previously, determines the inductance of coils 9 and 10 and hence the tuning of the receiver.

In addition to serving as a manual tuning means, the knob 13 may be turned to adjust the position of the other stop members 22 in turret assembly 23 so that all of the stop members 22 may be in suitable position for tuning when the foot operated switch 15 is actuated.

After the signal received on antenna 5 is suitably amplified and heterodyned in stage 47, the modified signal is impressed on the primary winding 48 of transformer 49, the secondary winding 50 of which has one of its terminals connected to the diode plate 51 and its other terminal connected to the grounded cooperating cathode 52 through the serial circuit comprising fixed loading resistance 53, lead 54, conventional volume control resistance 55, and lead 54A. Bypass condenser 53A is connected in shunt to serially connected resistances 53 and 55 for bypassing currents of superaudible frequency. The volume control resistance 55 has its variably positioned tap connected to grid 56 through lead 54B and through coupling condenser 57 to supply a selected fractional portion of audio frequency voltage detected in diode 51, 52 and appearing in the previously mentioned serial circuit across leads 54A, 54B to the amplifying section of the diode-triode device 58 comprising the diode elements 51, 52 and the triode elements 52, 56 and 59—the triode anode.

The triode 52, 56, 59 is supplied with space circuit through load resistance 59A from source 60 having its positive terminal connected to anode 59 and its negative terminal grounded. Amplified voltages appearing on anode 59 are transferred to another audio frequency amplifier stage 61 through coupling condenser 62.

The amplifying characteristics of the amplifying circuit including triode 52, 56, 59 may be controlled in a manner described presently to prevent for a predetermined time interval the transmission of detected audio frequency voltage from leads 54A, 54B to the amplifying stage 61.

It is noted that the grid 56 is connected to ground through a grid leak resistance 63 which has connected in shunt thereto a first series circuit comprising resistance 64 and condenser 65 and also in shunt thereto a second series circuit comprising decoupling resistance 66 and condenser 67 for performing a desired control operation. Condenser 67 is arranged to be charged with its ungrounded terminal at a potential sufficiently negative to produce stoppage of space current through the triode 52, 56, 59 and for that purpose the ungrounded terminal of condenser 67 is serially connected to the ungrounded negative terminal of voltage source 41 through the series circuit including lead 68, normally open switch 69 having contacts 70, 71 and 72 and resistance 73. Condenser 74 having its ungrounded terminal connected to lead 75 connecting switch contact 70 to resistance 73 is not essential to the practice of the present invention in its broadest form, but is desirable as will be explained later to obtain a predetermined timing interval regardless of the duration of contact between switch contacts 70 and 71. Suffice it to say for the present that the presence of resistance 73 plays an important role immediately after switch contact 71 is disengaged from grounded switch contact 72 but remains in engagement with switch contact 70 and the presence of condenser 74 assures a predetermined timing interval upon closing of switch contacts 70 and 71.

Resistance 64 and condenser 65 are not vital to the practice of the present invention in its broadest form but certain desired operating advantages are produced in that their presence insures quietness of operation of the receiver when the core members 11 and 12 are in transit from their furthermost left position in Fig. 2 to their arrested position wherein rod extension 21 contacts one of the selected stop members 22. For that purpose the ungrounded terminal of condenser 65 is connected to the ungrounded negative terminal of source 41 through the normally open switch 38 having the contacts 36 and 37. It is clear that in operation of the tuner 4 when switch 38 is closed condenser 65 is instantaneously charged to a negative potential assuring a cutoff of space current in triode 52, 56, 59, and that after opening of the switch 38 the condenser 65 remains charged and triode 52, 56, 59 remains inoperative to amplify signals for a time interval depending upon the time constant of the circuit permanently connected to condenser 65, such time constant being in the order of one-fifth second, a time sufficiently large to allow tuning cores 11, 12 to return from their extreme left position in Fig. 2 to their extreme right position to prevent undesirable noise in the interim.

In the operation of the delayed muting switch 69, it is clear that when insulated switch contact 70 remains in its normal position in Figs. 2 and 3 for a prolonged period condenser 74 assumes the potential of source 41 and that thereafter when the insulated contact is moved downward to the position shown in Fig. 4 wherein contacts 70 and 71 abut, the charge initially stored in condenser 74 is instantaneously distributed in condensers 74 and 67, condenser 67 assumes a voltage sufficiently negative to cut off the flow of space current in triode 52, 56, 59 and thereafter when the switch contact 70 is allowed to return to its normal position shown in Fig. 1 the device 52, 56, 59 remains inoperative to suitably transmit signals a time interval determined by the time constant of the circuit permanently

connected to condenser 67. This time interval is preferably of the order of thirty seconds and can be controlled easily by adjusting the magnitude of condenser 67.

In case it is desired to terminate the action of delayed muting once it has been initiated, switch contact 71 is moved to the position shown in Fig. 5 wherein insulated contact 70 is in contact with spring contact 71 and flexes it outwardly to where it engages the contact 72 which in reality is the inner wall of the grounded control housing. Switch contact 71 is sufficiently flexible to serve this function without interference in its function produced from spring 76 described later. When positioned as shown in Fig. 5, switch 69 serves to short-circuit condenser 67, the charge therein is dissipated and device 52, 56, 59 becomes immediately operative to transmit signals. Normally, when the switch 69 returns from the position shown in Fig. 5 to the position shown in Fig. 4, and then to the normal position shown in Fig. 3, in order that the condenser 67 may not be charged appreciably during the moment when the switch is in the intermediate position shown in Fig. 4, the resistance 73 is made of sufficiently large magnitude to allow only a negligible amount of charge to flow into condenser 67 during such moment.

As an example, in one practical embodiment of the present invention satisfactory delayed muting action was obtained when the triode elements 52, 56, 59 were incorporated in a so-called discharge device of the type commonly known as the 7B6, resistances 63, 64, 66 and 73 had magnitudes respectively equal to 15, 1, 1 and 1 megohms and condensers 65, 67 and 74 equal magnitudes respectively equal to .02, 2 and 2 microfarads.

Provisions are made also in the arrangement shown in Fig. 2 to produce a muting action by holding a switch in circuit closing position, such muting action continuing until the switch is allowed to assume its normally open position. For this purpose one terminal of the speaker 6 is grounded and the other terminal is connected to ground through the lead 77, switch 81 comprising the contacts 16, 83, the latter switch contact being grounded through the housing for control 1.

The control 1, preferably arranged on the floor board of an automobile but which may be arranged at any other suitable place in the automobile, for example on the steering post for knee, finger or leg operation or on the dashboard for finger operation, includes not only the volume control potentiometer 55 but also normally open switches 69, 81 and 15, all of which are closed in that order by depressing the control knob 8 and are opened in reverse order when and as the control knob 8 is returned from its furthestmost depressed position to its normal position.

Rotation of the control knob 8 produces a change in setting of the volume control potentiometer 55. The structural features of control 1 for effecting the above described control arrangements are described now. In general, the control 1 is constructed identically to the control which I have disclosed in Fig. 6 of my prior Patent 2,374,873, but is modified to incorporate the switch 69 for producing delayed muting and for stopping such delayed muting at any time at the wish of the operator.

The switch contact 16 is carried by a spiral spring member 88 and the contact 17 is secured upon a contact supporting strip 89. A wafer-like

contact assembly 91, comprising sheets of insulating material 92 and 93, is secured to the base plate 94 of the switch by tubular rivets or other suitable fastening means 96. The rivets 96 also serve to secure the sheets 92 and 93 together so as to retain the contact strip 89 in position between them. An ear 99 on the strip 89 provides a terminal to which the conductor 84 may be integrally secured in a permanently conductive member as by soldering or welding. The spiral spring member 88 is fastened to the insulating sheet 92.

The cup-shaped contact enclosing member 104 is adapted for connection to the base plate 94 by eyelet connections 106 or other suitable securing means. The reciprocable and rotatable contact 83 is guided for longitudinal movement by a guide bushing 108 of insulating material which is crimped to an aperture located substantially concentrically with the apertures in the contact supporting members 88 and 89. A disc or washer 109 surrounds the reduced portion 111 of the circular body of the contact 83. The spring 76 presents two substantially flat ends, one of which rests on the member 104, and the other rests against the washer 109. The washer 109 fits slidably in a cylindrical housing 116 which has an inwardly turned flange 117. Outward movement of the washer 109 is thus limited to thereby hold the spring 76 partly compressed. The housing 116 may be secured to the top of the contact enclosure member 104 by welding its outwardly turned flange 119 to the enclosure member. A cylindrical sleeve 121 surrounds the reduced portion 111 of the contact 83 and rests on the washer 109. This sleeve is surrounded by another spring 123 which is lighter than the spring 76. The aperture provided at the top of the housing 116 is large enough to accommodate the spring 123. The combined operating knob and button 8, comprising the cup-shaped member 125 and the annular member 127, is riveted onto the top of the contact member 83 as indicated by reference character 128. The annular member 127 is knurled or otherwise formed to provide a roughened surface as indicated by reference character 129, so that it may be rotated by the foot of the person desiring to control the volume of sound emitted by the loud speaker 6 of the radio receiver. The cup-shaped member 125 overlaps the housing 116 to prevent dirt and foreign matter from entering the switch. After the mechanical connection at point 128 is made, the spring 123 is held in compression between the combined knob and button 8 and the washer 109. The portion of the contact 83 which provides the permanent connection 128 is preferably square in cross section to fit a square aperture in the cap member 125, thereby to insure rotation of the contact 83 when the combined operating knob and button is rotated. It will be understood that any irregular shape in cross section may be given to the portion of the contact 83 which provides for the riveted connection for the purpose of insuring rotation of the contact 83 with the combined knob and button 8. For that purpose, contact member 70 is in the form of an annular ring insulated from contact member 83 by means of insulation 70A. The switch casing is connected to ground. The movable contact 83 of the switch is electrically connected to the grounded base plate 94 through the members 104, 116, 109, 123 and 125.

Upon exertion of pressure on the combined operating knob and button 8 to reciprocate the con-

tact 83 toward circuit closing engagement with the contact 16; the top of the sleeve 121 is engaged by the inner surface of the combined knob and button following initial compression of the spring 76.

At this time the contact 83 is in full circuit closing engagement with the contact 16, completing a circuit from the speaker voice coil to ground by grounding the conductor 77 and thereby muting the speaker. At this point in its movement, the contact 83 has not brought the contact 16 into circuit closing engagement with the contact 17. Further movement of the combined knob and operating button 8 causes the spring 114 to be compressed since there is now a direct connection between the knob and operating button 8, the sleeve 121 and the washer 109. Because of the added resistance of the spring 114, the operator can sense the point at which the circuit of conductor 77 has been closed and the closing of the circuit of conductor 82 is about to occur. Additional movement of the contact 83 will cause the contact 16, which is now grounded by the contact 83, to engage the contact 17 to complete the circuit including the conductor 82.

The volume control section 55 of the control I includes a volume control rheostat described previously which may be of any well known type, adjustable by rotating its operating shaft 133. The rheostat is shown as being secured to a bracket 134 by means of a nut 136. The supporting means for the rheostat just described is convenient since volume control rheostats are readily available which are of the panel mounted type shown, employing the nut 136. However, it will be understood that any type of rheostat may be mounted in any desired manner on the control I with its operating shaft projecting upwardly into the body of the switch as shown in Fig. 2 of the drawings, or the combination of a switch and volume control may be effected in other ways. To prevent ingress of foreign matter into the volume control section 55 and the various contacts, a cover member 137 is provided which encloses the rheostat 55 and the switch contacts.

The operating shaft 133 of the rheostat is slotted or bifurcated as shown at 138 so as to provide an extensible driving connection with a pin at 139 projecting from side to side through a bore 141 in the end of the contact 107. The extensible connection provided between the bifurcated end of the shaft 133 and the pin 139 permits the contact 107 to be moved longitudinally in the manner explained above to control the circuits of the conductors 82 and 84. Rotating the combined knob and button 8 will adjust the volume of sound emitted by the loud speaker. This is preferably to be accomplished by foot operation as explained above. The set may be muted at any time in the manner pointed out above irrespective of the angular position of the rheostat shaft 133.

Figs. 6-8, inclusive, show mechanical means in different operating positions for producing a desired control operation of the type described above. The mechanical means shown are preferably mounted on the floor board of an automobile for easy actuation by the foot of the driver but may be mounted elsewhere, for example on the steering post for leg, foot or finger operation or on the dashboard for finger operation.

Fig. 6 shows the mechanical means including a depressible cap 140 in its normal position with switch 135 comprising contacts 142 and 143 in

normally open position, while Fig. 7 shows the switch 135 in its closed position and Fig. 8 shows the position of cap 140 after it has been allowed to return to its normal position but before it reaches its normal position and with switch 135 still in its closed position. The switch contact 142 is grounded through the housing 144 while insulated switch contact 143 is connected by lead 157 to the ungrounded terminal of the voice coil of a speaker as shown in Fig. 2 so that when switch 135 is closed the transmission of sound to the speaker is prevented.

The cap 140, having fastened thereto by means of screw 146 the inner flanged hollow cylindrical member 147, is normally pressed upwardly by compression spring 148 to a position where the upturned flange member 149 engages the inwardly turned edge 150 of the cylindrical housing 144 and limits upward movement of cap 140. Mounted upon member 147 by means of, for example, rivets 151 is a washer 152 which has sandwiched tightly between member 147 and washer 152 leather packing material 153 with a portion extending therefrom to form a substantially airtight connection between the inner wall of cylindrical housing 144 and the outer edge of washer 152 in all positions of the cap 140 and attached washer 152. The inner edge of washer 152 serves an important function as will be described later to produce contact with and movement of the enlarged cylindrical head 154 of combined rod and switch element 142. Mounted upon the base of housing 144 by means of, for example rivets 155, is insulating member 156 having in turn mounted thereon switch contact 143 and lead 157 in such a manner that a substantially air tight connection is made at the base of housing 144.

Washer 152 and insulating member 156 form a seat for the compression spring 148 which is substantially "stiffer" than a second compression spring 158 concentrically mounted therewith in housing 144, spring 158 exerting in all positions thereof a force between its seats comprising washer 152 and a flange on rod 142. The housing 144 is preferably fixedly mounted on its supporting member, for example the floor board of an automobile, and it is seen from the structure thus far described that cap 140 may be moved relative to housing 144 and also that combined rod and contact member 142 may move relative not only to housing 144 but also relative to cap 140 up into the opening 159 in member 147.

It is noted also that the chamber 160 enclosed by housing 144 is substantially air tight and that an adjustable needle valve 161 screwthreadedly mounted on housing 144 furnishes a controllable orifice for the controlled flow of air from the chamber 160 into the atmosphere surrounding chamber 144.

When the cap 140 is depressed by means of, for example the foot of the driver of an automobile from its normal position shown in Fig. 6 to its extreme downward position shown in Fig. 7, the attached washer 152 of course also moves downward, the stiffer spring 148 is compressed, air is forcibly pressed out of the needle valve 161, the switch contact 142 moves downwardly until it engages fixed contact 143, and then further downward movement of the cap 140 requires an additional force and more than a linear change in force not only to compress spring 148 further but also to begin to compress spring 158, in which case movement of rod or contact 142 is arrested

and there is relative movement between member 147 and rod 142 in the opening 159 in which case rod 142 approaches its extreme position as shown in Fig. 7. It is thus clear that an operator is warned in pressing cap 140 downward of the engagement of switch contact 142 with switch contact 143 by a noticeable change in force required thereafter to move the cap 140 downwardly.

After the control shown in Fig. 7 is released from its extreme position shown therein, the springs 148 and 158 exert a force to move the cap 140 upwardly, but such upward motion of cap 140 is retarded by the fact that the needle valve 161 restricts the flow of air and a partial vacuum exists in chamber 160 due to upward motion of the cap, and as a consequence the force of springs 148 and 158 acts against an air pressure which may be controlled by adjustment of the needle valve 161. When and as the cap 140 moves upwardly, it is noted that the spring 158 continues to press contact 142 into engagement with contact 143 with the result that the opening of switch contacts 142, 143 is delayed until the washer 152 moves upwardly a sufficient distance to engage the enlarged head 154 on rod 142 and to move rod 142 upwardly also out of contact with fixed switch contact 143.

It is thus clear that when the cap 140 is depressed to its furthermost position and then released, the switch 135 is closed and remains closed a predetermined time interval which may be as much as one minute after the cap is allowed to return to its normal position under the influence of springs 148 and 158. It is also clear that this time interval may be adjusted by adjustment of needle valve 161.

It is also clear that the operator of cap 140 may sense readily, by the sense of touch, the instant contact 142 engages contact 143. This feature allows the operator to effect a shorter time interval of closure of switch 135 than the maximum time interval determined by the opening in needle valve 161. To effect such a shortened closure of switch 135, the operator simply does not press the cap all the way down after sensing, by the sense of touch, the closure of switch contacts 142 and 143. Preferably, in the operation of the mechanical dashpot control described, the cap is pressed all the way down to its extreme position shown in Fig. 7 and then released.

In the modification shown in Fig. 9, the receiver shown in Fig. 2 is muted for a predetermined period of time by pressing the cap 162 downwardly, for example by the foot, leg or finger of an operator of a vehicle. In Fig. 9, the switch 163, comprising the contacts 164 and 165, finds its counterpart in Fig. 2 in the switch 69, comprising the contacts 70 and 71, and the switch 166 in Fig. 9 comprising the contacts 165 and 167 finds its counterpart in the same switch 69 of Fig. 2, comprising the contacts 71 and 72. The leads connecting these corresponding switch contacts in Figs. 2 and 9 bear the same reference numerals.

The control of Fig. 9 serves only for producing delayed muting of the type described herein and rendering such delayed muting ineffective in the manner described in connection with the description of Fig. 2. One important feature of the control of Fig. 9 is that it allows the operator to sense, by his sense of feeling, engagement of contact 164 with contact 165 and the instant delayed muting begins. Further downward

movement of the cap 162 from its delayed muting position results in contact between contacts 165 and 167 and rendering ineffective the action of associated circuit of Fig. 2 in producing such delayed muting.

The structure of the control shown in Fig. 9 bears some resemblance to the similar control shown in Fig. 2 as will be evident from the following description.

The switches 163 and 166, the parts of which are shown in section by Fig. 9 of the drawings, include a base plate 168 to which is secured by tubular rivets 169 a wafer-like contact assembly 170 comprising sheets of insulating material 171 and 172 secured together also by rivets 169. The contact member 167 is secured on a protuberant portion of the metallic strip which is retained between the sheets 171 and 172. Ear 173 on the strip provides a terminal to which the conductor 174 may be integrally secured in a permanently conductive manner by soldering or welding. The contact 165 is secured on a resilient member such as a spiral spring 175 which is secured to the insulating sheet 171 by means of, for example eyelets.

The cup-shaped contact enclosing member 176 is apertured for connection to the base plate 168 by eyelet connections 177 or other suitable means. The eyelet connections shown possess the advantage of receiving bolts, screws or other connecting means for securing the composite control to the floor board or other part of the vehicle, and also, the control may lie closely in contact with the vehicle floor board or other part. A guide bushing 178 of insulating material is crimped to an aperture 179 located substantially concentrically with respect to the contacts 164, 165 and 167. The guide bushing 178 serves a three-fold purpose in that it provides an insulating abutment for the contact spring 175, serves as a guide for the contact 164 and positions a comparatively powerful contact biasing spring 180. The spring 180 presents two substantially flat ends, one of which rests on top of the member 176 and the other of which reacts against a disc or washer 181 which surrounds the reduced portion 182 of the circular body of the contact actuating rod 183 which has fastened permanently thereto by means of insulating member 184 the contact 164. The disc 181 preferably has an outside diameter such that it fits slidably in the cylindrical housing 185 which has an inwardly turned flange 186 providing a restricted portion which serves to limit outward movement of the washer 181 and thereby holds the spring 180 partly compressed. It will be seen from this that the movable contact actuating member 183 is guided for longitudinal movement. At the end of the housing 185 opposite the flange 186 is an outwardly turned flange 187 by means of which the housing is fastened by welding or other suitable means to the top of the contact enclosure member 176. Above the washer 181 is a cylindrical sleeve 188. This sleeve is surrounded by another spring 189, which is lighter than the spring 180, and the whole is enclosed by the operating button 162 which is riveted onto the top of the contact actuating member 183 at 190. The operating button 162 overlaps the associated housing to prevent dirt and foreign matter from entering the switch body. In this manner the spring 189 is somewhat compressed under ordinary conditions. Upon exertion of pressure on the operating button 162 to move the contact 164 to-

ward circuit closing engagement with the contact 165, the spring 189 is compressed until the inner surface of the button 162 engages the top of the sleeve 188. At this time, the contact 164 is in full circuit closing engagement with the contact 165. This completes a circuit. In the circuit of Fig. 2 wherein the control of Fig. 9 is easily substituted by connecting leads of like reference numerals together, the circuit for delayed muting is accomplished. At this point, the contact 165 has not yet engaged the contact 167. Further movement of the operating button 162 must necessarily cause compression of the spring 189 since there is now a direct connection between the button 162, the sleeve 188 and the washer 181. The added resistance of the heavier spring 189 enables the operator to sense the point at which a first circuit has been closed and the closing of the circuit including contact 167 is about to occur. Upon additional movement of the contact 164, the contact 165, which is now engaged by the contact 164, engages the contact 167 to complete the circuit to be controlled to cut off the period of delayed muting initiated by engagement of contact 164 with contact 165.

It is apparent that when the teachings of the present invention are utilized other mechanical arrangements suggest themselves. For example, mechanisms identical or similar to those found in the so-called fully automatic bread toasters in household use may be utilized. As a further example, as shown in Fig. 10, depression of the control rod 195 which may be attached to one of the depressible control buttons or knobs in the other figures serves to store energy in a coil clock spring 196. Upon release of rod 195 to allow it to assume its normal position shown in Fig. 10, the energy stored in spring 196 not only serves to return control rod 195 to its normal position but serves also to maintain the centrifugally actuated switch 197 comprising contacts 198, 199 in closed position to ground lead 77 connected to the ungrounded terminal of the associated loud speaker for a predetermined time interval in the order of, for example thirty seconds. For this purpose, the rectilinear movement of control rod 195 is converted into rotary movement of shaft 200 by means of the connection between rack 201 and pinion 202. An overrunning clutch designated as 203 which may be a simple pawl and ratchet arrangement serves to rotate weights 204 from the energy stored in clock spring 196 having its free end attached to shaft 200 and its other end permanently fastened in place. Upon rotation above a predetermined speed of weights 204 mounted on a resilient element 206, weights 204 move outwardly from the axis of rotation due to centrifugal forces acting thereon to move the switching disc 199 to the left against cooperating switch contact 208 to close an electrical circuit. The time interval which switch 197 is thus closed may be adjusted by adjusting the position of contact 198 to control the amount of friction between contacts 198 and 199.

It is clear from the description above that when the control rod 195 is moved downwardly the shaft 200 is rotated, energy is stored in spring 196 but weights 204 are not rotated because of the presence of the overrunning clutch 203. But then, upon release of the control rod 195, the energy stored in spring 196 moves the control rod 195 upward to its normal position, the weights 204 are rotated until substantially all of the energy stored in 196 is dissipated as frictional

heat in the contacts 198 and 199. It is clear also that shorter times of switch closure than the predetermined times determined by full winding of spring 196 may be produced by moving control rod 195 downward but not to its most extreme position, in which case the spring 196 is partly wound and switch contacts 198, 199 remain closed a much shorter time.

In order to cut short the period of "delayed muting" or in order to render the action of "delayed muting" entirely ineffective, the switch 205 may be opened, in which case the associated speaker coil is not short circuited by the delayed muting mechanism described.

15 While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

25 1. In combination, a normally operative sound amplifying device, a control element movable continuously from its normal position through an intermediate position to a third position, means actuated upon movement of said control element to said intermediate position to render said device inoperative to suitably transmit amplified voltages, said last means having inherent time delay means connected thereto to automatically render said device operative again a substantial time interval after movement to said intermediate position, and means actuated upon movement of said control element to said third position to automatically restore said device to operative position without waiting for the elapse of said time interval.

30 2. The invention defined in claim 1 characterized by spring means actuated upon movement of said control element allowing an operator thereof to determine, by the sense of feeling, the position of the control element.

35 3. The invention defined in claim 1 characterized in that a pair of spring means is operated by said control element, said spring means being of differing resiliencies thereby allowing an operator to determine by the sense of touch the position of the control element.

40 4. The invention defined in claim 1 characterized in that a pair of spring means is operated by said control elements, one of said spring means being compressed upon movement to said intermediate position and said second spring means being compressed upon movement to said third position, thereby allowing an operator to determine by the sense of touch when said control member has reached said intermediate position and is moving from said position to said third position.

EUGENE F. McDONALD, JR.
